UNITED STATES PATENT OFFICE.

WILLIAM D. GHERKY, OF PHILADELPHIA, PENNSYLVANIA.

GRINDING-MACHINE.

1,096,005.

Specification of Letters Patent.

Patented May 5, 1914.

Application filed November 9, 1911. Serial No. 659,456.

To all whom it may concern:

Be it known that I, WILLIAM D. GHERKY, a citizen of the United States, residing at Philadelphia, in the county of Philadelphia, and State of Pennsylvania, have invented certain new and useful Improvements in Grinding-Machines, of which the following is a specification, reference being had thereto to the accompanying drawing.

10 My invention relates to grinding machines, and especially to those designed for grinding the surfaces of railway rails in place.

15 It has for its object the production of a machine of this class capable of meeting the following conditions: to be compact, self-contained, and within the power of manipulation of one or two men; to grind either or both rails of a track simultaneously, at will; to be self-propelled and self-governing, so that when set it will automatically travel back and forth over any selected portion of the rail within a distance predetermined by its own adjustment; to be self-regulating

25 and self-feeding in respect to the cut, i. e. the depth to which the rails will be ground, the feed being direct and reversed so as to give automatic running-on and running-off or tapering of a cut; to permit ready and accurate adjustment of each grinding wheel to compensate for wear irrespective of its 30 feed, or operating travel; to permit the quick and easy replacement of grinding wheels when desired; to be readily and quickly de-

35 tachable from a rail at any point in its operation, movable therefrom to permit the passage of a car, and instantly returnable thereto without loss of adjustment or position in its further operation; to be readily convertible from a tapered cut to a straight cut, or any desired combination of the two; to be adjustable to any gage of track; to be balanced in its parts and in the design of each part so as to be substantially free from noise 40 or vibration; to be raised, suspended, and transported on road wheels by relatively low power; to be free from danger to the operator in its ordinary manipulation, certain, economical and efficient in its action.

45 Stated in structural terms the invention which I hereby present attains my object and meets the foregoing conditions as follows: I provide a duplex grinder having a substantially square steel frame constituting a truck upon which are mounted a motor, drive and counter shafts, reducing gears, re-

versing motions, adjustable flanged track wheels, double swung and doubly adjustable vertically feeding grinding wheels driven from the motor, reversible transmission gear for producing oscillating travel of the truck on the rails, hoisting and suspension gears and a trolley pole with connections for supplying power to the motor where the latter is electrical, or a suitable source of energy 60 supply when the motor is of some other type. In addition to these parts, which are all compactly arranged upon the truck frame, a pair of road wheels of large diameter is provided, connected to the frame by hoisting mechanism so arranged with suitable gearing that the machine can be hoisted upon these wheels and the wheels turned by relatively small power.

70 The grinding wheels are run separately so as to grind either one or both of the track rails of a pair at will and each is separately detachable from the power mechanism, as well as separately and individually adjustable.

75 In order to be self-propelling and self-governing, the machine is provided with gearing connecting the motor to the track wheels through clutch mechanism, and a timing mechanism is also connected to the 80 motor and driven thereby controlling the clutch mechanism so as to produce direct and reverse action on the driving wheels alternately; the time of this action being determined by the adjustment of the operating 85 connections between the timing mechanism and the clutch. The grinding wheels are rendered self-feeding by connecting the timing mechanism with an adjustable actuating member engaging a spring pressed cradle 90 carrying each wheel. To compensate for wear on the wheels, each wheel is mounted in a vertically adjustable member pivoted on its cradle and adapted to be locked thereon when set, so as to move with the cradle 95 during the feed.

100 To permit the ready replacement of the grinding wheels, each wheel is formed as a ring, the grinding material of a radial depth determined by the permissible variation in 105 peripheral speed at a given number of rotations, each ring being clamped in metal hub plates adapted to be readily slipped into and out of the cradles.

110 To permit the machine to be removed from the rail at any point in its operation and replaced thereon at precisely the same

the motor 9 and its connected parts. This machine being intended for use on electric roads, an electric motor is employed, the detailed construction of which forms no part 5 of the present invention, but which drives a shaft 10, provided with suitable out-board bearings and driving a suitable train of reducing gears shown for simplicity as a worm 11, meshing with a worm-gear 12, which is fixed upon a driving shaft 13, from which 10 power is taken to propel the machine on the tracks, and to feed the grinding wheels to be presently described. On its opposite ends the motor shaft 10 carries belt-pulleys 14, 15, from which power is directly communicated 15 to similar pulleys 16, 17, on the grinding wheel spindles. As will presently appear, the grinding wheels are capable of lateral adjustment in the frame to accommodate 20 tracks of different gages, and to permit this adjustment without interfering with the drive, the belt-pulleys, 14, 15, on the motor shaft are given endwise adjustment, as indicated in dotted lines.

25 The machine is supported upon the track rails by a pair of track wheels, 18, 19, and a pair of travelers, 20, 21. The track wheels are splined or otherwise secured for longitudinal adjustment on an axle, 22, having 30 end-bearings, 23, 24, on the frame. The travelers, 20, 21, are secured directly beneath the ends of the cradles which carry the grinding wheels, and are laterally adjustable therewith, so that all adjustments for gage 35 are parallel and can be made accurately without any danger of throwing the parts out of line.

The grinding wheel drive is always in the same direction, but in order to run the machine back and forth over the section of the rails to be ground, a reversible drive is required for the track wheels and their axle, and this is provided in the following manner: The driving shaft, 13, carries a pinion, 25, which meshes with a gear-wheel, 26, on a short shaft, 27. This shaft carries a pinion, 28, which meshes with a gear-wheel, 29, on a shaft, 30. The shaft, 30, carries a miter-gear, 31, which meshes with companion 45 miter-gears, 32 and 33, traveling loosely in opposite directions upon the axle, 22, and adapted to be coupled thereto alternately by means of a sliding clutch, 34, controlled by 50 a fork, 35, on a swinging lever, 36, pivoted at 37 to the frame member 4. With this arrangement, by swinging the lever 36, in one direction, the gear 32 will be coupled to the axle, and the machine will be slowly driven along the track through any desired distance. By then reversing the throw of the 55 lever 36, the gear 32 is disengaged, and the gear 33 coupled to the axle, so as to reverse the motion of the machine by driving the track wheels, 18, 19, in the opposite direction. This reversal is made automatically,

by means which are adjustable to permit any desired travel or amplitude of oscillation of the machine as a whole. These means are as follows: A sliding bar, 38, has a central slot 39 through which the lever 36 passes. It 70 also has at one end a slot 40, receiving a pin 41 on the lower arm 42 of a bell-crank lever, whose upper arm 43 has its end 44 projecting through a slot 45 in the lever 46 pivoted at 47 to the frame, and oscillated up and 75 down by means of an adjustable wristpin connection 48 on a rocker-arm 49 secured upon a short shaft 50 carried in bearings 49^b and which also carries a toothed segment 51 secured to a hub 52 and driven by a pinion 53 on one end of a shaft 54, which carries on its other end a gear-wheel 55 meshing with a pinion 56 fixed on a loose sleeve 57 adapted to be coupled to the axle 22 by means of a clutch 58 having its sliding member 59 85 splined on the axle and worked back and forth by means of a fork 60 on one arm of a bell-crank lever 61, the other arm of which is connected by means of a link 62 with a rocker-arm 63 on a shaft 64 extending clear 90 across the frame, and having at opposite sides thereof vertical hand-levers 65, so that the clutch 58 can be thrown in or out of engagement by hand from either side of the machine. The operation of this part of the 95 machine is as follows: Power being communicated to the axle 22 in one direction or the other through one of the miter-gears 32, 33, is thereby communicated, when the clutch 58 is closed to the pinion 56, and thence to the 100 intermeshing gear-wheel 55 and its shaft 54. The pinion, 53, is thus turned very slowly, and turns the segment, 51, up or down according to the direction of its rotation. As the segment moves, it rocks the shaft, 50, 105 and thereby the arm, 49, which moves the pivoted lever, 46, which in turn rocks the bell-crank, 43, and after a certain amount of travel of the pin, 41, on the arm, 42, in the slot, 40, (Fig. 2) the sliding bar, 38, is moved 110 to shift the clutch-lever, 36, so as to disengage the clutch and start it to reverse. To make this reversal certain, and also to permit intermediate travel of the parts between 115 reversals, I provide a weighted lever, 66, pivoted on the frame at 67 at its lower end, and also pivoted to the bar, 38, at 68, without lost motion. The weight on the lever is indicated at 69, and these parts are best shown in Fig. 2^a. When the pin, 41, on the bell-crank, 42, reaches the end of the slot, 40, in either direction, it pushes the bar, 38, and with it the weighted lever, 66, until the latter goes past center, whereupon the weight, 69, in falling, will carry the lever, 66, to the end of 120 its stroke, pulling with it the bar, 38, and completing the movement of the clutch parts, 36, 35 and 34.

The parts thus described are all so related 130 that when the segment, 51, is in its inter-

to regulate the depth of its cut. This raising and lowering progresses gradually, as the machine travels back and forth over the track rails, and permits the accurate formation of "tapers" or "run-offs" in opposite directions from the deepest part of the cut. In order to make the taper or run-off coincide perfectly in its longitudinal dimension with the amplitude of travel of the machine, 5 it is only necessary to properly connect the shaft, 103, to the driving gear, with suitable reversing means, and this is done in the following manner: The shaft, 103, has a rocker-arm, 105, fixed upon it, carrying a wristpin, 106, upon which is pivoted one end of a link, 107, the other end of which is pivoted on a similar wristpin, 108, carried on a rocker-arm, 109, which is fixed upon the shaft, 50, carrying the segment, 51. Both 10 the wristpins, 106 and 108, may be and preferably are made adjustable radially with respect to the shafts on which they are fixed by providing sliding blocks and screws similar to 48^a, 49^a of arm 49, in their rocker arms 20 105 and 109, and by adjusting these blocks in and out, the amplitude of oscillation of the pins 106 and 108 may be accurately determined. Hand wheel 109^a is connected to its screw by miter-gears in order to clear the 25 gearing.

It should be borne in mind that the segment 51 is slowly rocked up and down as the machine travels back and forth. Each complete movement of the segment up or down 30 before reversing, represents and coincides with the travel of the machine in one direction. The rocker-arms, 109, 105 and 102, are set upon their shafts with respect to each other, so that the arm 102, will start from 35 one end of its travel, push the cradle down to the lowest point, and in swinging to the other end of its travel will raise it again, during one complete movement of the segment 51 up or down. In other words, as the 40 machine starts from one end of its travel and progresses along the track, the grinding wheel will be slowly fed down until it reaches the deepest part of the cut, and then 45 will be slowly fed up again to reach its uppermost position at the same moment that the machine reaches the end of its travel and 50 starts to reverse, the reversal being brought about it will be remembered, by the action of the clutch 34 in Fig. 1.

The accuracy of the cut made by the 55 grinding wheel is determined always with respect to the normal surface of the rail, and in this determination no account can be taken of individual corrugations or inequalities, as otherwise the grinding wheels would 60 produce corresponding inequalities. To eliminate such a chance, and to afford an accurate support regardless of short waves or depressions, I provide the ex-

tended traveler 20 which of course is duplicated on the other side of the machine. This traveler is for convenience mounted upon the same shaft 88 which supports the cradle, and is laterally adjustable with it so as to be kept always in line with the grinding wheel 70 and the track wheels. It may be here stated that these parts all travel laterally together, the abutment 101, which supports the spring 100 being secured to the frame channel 6, the spring 100 is guided thereover in its 75 lateral movement by means of a boss cast upon the lower surface of the projection 86^a of the cradle member 86.

The traveler 20 is made longer than any corrugation or ordinary track depression, so 80 as to bridge the same and effect an extended support upon the average or normal surface of the rail. The traveler may slide directly on the rail, but I prefer to provide it with a plurality of rollers, indicated at 20^a, and 85 one or more of these rollers may be fitted with flanges as indicated at 20^b, for the purpose of maintaining alignment on the rails. It is to be especially noted that a single 90 roller would be inoperative for my purpose, as it would afford only a single point or transverse line of contact with the rail. I consider this extended plurality of rollers therefore to be an important feature of my 95 invention, and I shall claim the same accordingly.

Another point to be noted with respect to the traveler 20, is its nearness to the grinding wheel, relative to the spacing of the latter from the track wheels. The latter have 100 no extended contact with the rail, but inasmuch as the effect of the traveler 20 and the track wheel 18 upon the adjustment of the grinding wheel 80, is inversely as the distances between centers, any effect produced 105 by the track wheel may be regarded as negligible, due to my method of spacing. I consider this also an important feature of my invention, especially in this combination self-contained machine, in which the supports on the rail are of a composite character, that is to say composed in part of propelling track wheels, and in part of cut-determining travelers.

The foregoing description covers the operating parts of the machine. There is still another feature, however, of great importance, which remains to be described, viz., means for independently supporting the machine and removing it from and replacing it upon the track. This means comprises a hoist, a pair of road wheels, and a power drive which can first be applied to the hoist and then to the road wheels, rendering it possible by small power to handle the entire 125 machine, remove and replace it, which so far as I am aware has never before been accomplished. Rising from opposite sides

verse action up and down, as embodied in the different elements mentioned, to be novel and original with me and shall claim the same accordingly.

5 The mechanism for turning the windlass comprises a pinion 144, fixed on the crank-shaft 145, which is journaled in bearings 146 and 147 carried rigidly on the hub 123 of the wheel 124; a gear-wheel 148 meshing 10 with the pinion 144, is secured to a drum 149, in which there is a notch 151, as best shown in Fig. 2. To engage with this notch a pivoted detent or dog 152 is provided, and the notch is so positioned that it will be engaged by the detent when the machine is 15 hoisted on the wheels 122 and 124, and also when the windlass and connected parts are hoisted on the machine. When the windlass is in neutral position, that is to say with both 20 wagon wheels and track wheels on a level as shown in the drawings, this notch is diametrically opposite the point of the detent or dog 152. A half revolution in one direction will then lift the wagon wheels and 25 hold them by the dog and notch, while a half revolution in the opposite direction will lift the machine and hold it by the same dog in the same notch. Secured to the windlass sleeve, 141, outside of the box 131, 30 is a friction disk 153, and outside of this disk is a wheel 154, having on its periphery ratchet teeth engaged by a pawl 155 pivoted on the box 131, as is also the detent 152. The ratchet wheel 154 is locked be- 35 tween the drum 149, and the disk 153, by friction due to the engagement of the screw-clutch 156, which in itself forms no part of the present invention, but is an important element in the combination employed.

40 In the drawing, I have shown the crank 135 provided with an extensible portion 135^a, pivoted so it can be swung in either direction, to make the crank long for working the windlass, and to make it short for turning the wheels 122 and 124. It should be 45 noted here that the pawl 155 is never lifted. The operation of these parts is as follows: Assuming that the machine is resting on the rails, and it is desired to move it, the wheels 50 122 and 124 being hoisted up. The dog 152 is first lifted, and the crank turned to rotate the gear-wheel 148 so as to unwind the chain on the windlass, whereby the wheels and axle are lowered. Continued opera- 55 tion of the crank then produces further winding of the chains on both ends of the windlass, so as to lift the machine bodily, and when this has been accomplished, the detent 152 engages the notch 151 in the 60 drum, and the parts are automatically locked. Continued rotation of the crank shaft will now result in rotating the pinion, 144, and the crank-shaft 145, in planetary fashion around the gear-wheel 148, and as

the road wheel 124 is fixed to the pinion bearings, it is turned also, and with it the axle 121 and the wheel 122. Thus the machine may be expeditiously rolled at right angles to the track to remove it from the path of an oncoming car. To replace the 70 machine, the crank motion is first reversed so as to reverse the planetary gear effect, and turn the wheels, 122 and 124, in reverse direction to again bring the machine over the track rails. The dog 152 is then lifted, 75 and the crank 135 slowly rotated backward to continuously keep the clutch parts 148, 149 sufficiently uncoupled to permit the windlass to turn slowly and lower the machine on the track. In so doing, the crank 80 cannot fly around, nor the machine be dropped suddenly, as any stoppage in the reverse motion of the crank will result in locking the screw parts 156. A chock 122^c (see Fig. 2^c), may be conveniently attached 85 to the rim of one of the road-wheels, as 122, by means of the hooked bolts 122^b. This chock serves as a reactive means to prevent rolling of the road wheels when the weight 90 of the machine is being hoisted thereon, and it also serves to accurately and expeditiously locate the machine over the rails after the same has been rolled aside to permit the passage of a car. Inasmuch as the road-wheels in practice make but half a 95 revolution to clear the car, the chock may remain on the road-wheel except when the machine is being transported over a distance greater than its circumference.

Connected to the sleeve 132 by a hand-wheel friction clutch 160 is a winding drum 161. The purpose of this drum is to wind up a cord 162 attached to the trolley pole of the machine so as to draw down the pole automatically when the machine is being hoisted 100 on the axle to permit an approaching car to pass. The trolley pole rigging is shown in Fig. 4, the cord 162 extending to a suitable sleeve 163 on the pole 164, which has at one end a fork 165 (or trolley wheel) to engage the trolley wire, and is secured near the other end in a sleeve 166 pivoted at 167 to the post 168. Outside of the sleeve a cap 169 is fitted to the end of the pole and carries 110 a T-head 170 with its ends projecting transversely to the pole, and each of them receiving a hook 171 on the end of one of a pair of springs 172, the other ends of which are secured to the opposite ends of a sliding cross head 173 secured by means of a set 115 screw or similar device 174 on the diagonal brace 175 which is secured at its lower end in a cast iron socket 176 on the machine bridge 120 and carries at its other end a bearing sleeve 177 in which the post 168 can 120 turn. The foot of the post is received and journaled in a cast iron socket 178 secured 125 on the bridge member 120 of the machine.

serve the function for which it is intended, and which is material and essential. This function is to cushion the suspension of the machine from the wheels 122 and 124 by suitable means interposed between the axle boxes 131, 131^a, and the upper ends of the vertical suspension frame 7-7^a 8-8^a, 120. Suppose the machine has been hoisted, so that the vertical frame pieces 7-7^a, 8-8^a have risen, with respect to the axle boxes 131, 131^a, obviously the space in each vertical slot between the axle box and the head or bridge member 120 will be much higher than normal. Into these spaces the boxes 186 are inserted, one on each side, and in order to prevent lateral displacement of the boxes under strain, suitable holding means may be provided therefor, in the shape of flanges or projections, either on the spring boxes or the axle boxes, or on the frame. The detent 152 may then be disengaged from the slot in the drum 149, and a few backward turns of the crank handle will impose the entire weight of the machine on the springs in the boxes 186, and the general arrangement will at once become quite similar to that of the frames and journal boxes on a railway truck. A great advantage gained by this arrangement is that the line of support for the entire weight of the machine is at its highest part, that is along the bridge member 120. This tends to lessen oscillation.

Means for transporting the machine are shown in Fig. 6, the arrangement being such that while the tractile force is applied directly to the axle 121, the frame of the machine is held to prevent excessive oscillation, and receives its due portion of the impetus due to the propelling force. Two draw bars 187, 188 are provided which may conveniently be steel tubes with solid ends welded to them, these ends being flattened and provided with bolt holes. The end 187^a is bolted between the projecting ears on a collar 187^b encircling the axle, and the end 188^a is similarly bolted between ears on a collar 188^b. The ends 187^c and 188^c are secured by a throughbolt with the head of a draw bar adjuster or link 189 between them. The lower end of this link is provided with a number of bolt holes by which it can be adjustably secured between a pair of ears on the frame member 3 or 4. The ends 187^c and 188^c project and are provided with bolt holes for the attachment of a link or other means for connecting the draw bars to the rear end of a wagon or truck or to a swing-tree for direct hauling. Thus, with the spring-suspension and steadyng link, the machine may be transported any distance with ease and security.

The method of control and the crank method of feeding, that is to say of regu-

lating both the travel of the machine and the depth of cut of the grinding wheel, which I have described, embody features of invention not found in machines heretofore suggested or in use. In addition, it should be particularly noted that the two cranks 49 and 109 are keyed to the same shaft 50, whereby their relation to each other is definitely fixed and their coöperation is therefore not dependent upon the exact timing of independently acting agencies. In the latter case, any variation in the time and travel of the machine, or the time of feed of the grinding element would result either in a reversal of travel without a perfect run-off or taper, or in carrying the grinding element too long out of contact with the rail before reversing the travel. Having these two cranks on one shaft also permits the use of one simple clutch 58 for controlling both feeds simultaneously and conveniently, as in passing from joint to joint or in working on corrugations.

It has heretofore been stated that the grinding wheels used in this machine are no more than rings on metal hubs. Figs. 4 and 5 show the construction of the wheel and hub. The hub is composed of a pair of matched plates as shown in section in Fig. 5, each notched around its periphery to form an annular channel, with an inwardly leaning flange. When these two plates are put together they form a circular dove-tail to receive the wheel, and they are secured together by bolts as shown in Fig. 5. When a wheel becomes worn, the upper member 100 of the cradle is lifted up to disengage its adjusting screw, the caps of the bearings are loosened, and the old wheel is then slipped out, its plates separated, a new ring of abrasive material clamped in the dove-tail 105 between them, and the latter then slipped into place in the cradle, which is readjusted for the new diameter thus created. In practice, several pairs of hub plates are provided with each machine, so that spares may be 110 kept loaded ready for insertion without delay when a wheel becomes worn and it has to be removed.

It will be noted that in Fig. 3^a just to the right of the grinding wheel 80, that is to 115 say, behind the wheel, which rotates in counterclockwise direction when viewed in Fig. 3^a, I provide a thin iron shield 86^c with a flexible asbestos end 86^b riveted to it. This sweeps the rail behind the emery wheel (in 120 the direction toward the driving wheel,) and in operation all of the white hot, semi-molten mass due to the grinding accumulates against the asbestos, and may occasionally be hooked out with an iron tool provided 125 for that purpose.

I am aware that many changes and modifications may be made in this machine with-

- of track rails, track wheels partially supporting said frame, a traveler fixed to the frame so as to partially support the same and accurately determine its alinement with respect to the rail, a grinding wheel carried on the frame in proximity to said traveler, means mounted on the frame to drive said grinding wheel, means also mounted on the frame for driving said track wheels, means for reversing said drive, a timing device controlling said reversing means, means for feeding the grinding wheel, an adjustable working connection from the timing device to said feeding means, and another adjustable connection between the timing device and the track wheel drive, whereby the depth of cut and the length of cut may be jointly and reciprocally varied at will in a predetermined manner.
8. In a machine of the character described, a truck frame adapted to travel along a track way, with single contact supports at one end, and a traveler rigidly connected to the other end at one side of the frame and having an extended bearing on the rail surface longer than any rail corrugation to be ground, said traveler forming the complete and sole support of the frame at its end, and a grinding element mounted on the frame close to the traveler and in position to engage the same rail of the track way.
9. In a machine of the character described, a truck frame adapted to travel along a track way, with single contact supports at one end, and vertically adjustable travelers attached to and constituting the sole support of the frame at opposite sides of the other end, each traveler having an extended bearing on the rail surface longer than any rail corrugation to be ground, and a grinding element mounted on the frame close to one of said travelers and adapted to be brought into engagement with the same rail as determined by the adjustment of said traveler, together with means to drive the grinding element.
10. In a machine of the character described, a truck frame adapted to travel along a track way, an axle at one end thereof carrying propelling wheels adapted to travel on said track way, means to drive said propelling wheels, and vertically adjustable travelers attached to and constituting the sole support of the frame at opposite sides of the other end, each traveler having an extended bearing on the rail surface longer than any rail corrugation to be ground, and a grinding element mounted on the frame close to one of said travelers and adapted to be brought into engagement with the same rail as determined by the adjustment of said traveler, together with means to drive the grinding element.
11. A machine of the character described comprising a main truck frame, auxiliary derailing wheels therefor by which the machine may be transported from the trackway, hoisting mechanism between the main truck frame and said auxiliary wheels, a single set of track supports for said main truck frame adapting it to travel along a trackway, said supports being permanently in position to engage said trackway when said main truck frame is lowered to the trackway from said auxiliary wheels, one of said supports at one end of the main truck frame having an extended bearing on said trackway greater in length than the length of any corrugation to be ground out, and another of said supports at the other end of said truck frame having a propelling wheel, and a grinding wheel mounted on said frame closely adjacent to said first named support and removed from said second named support.
12. The combination of a single truck frame, a driving wheel partially supporting the frame at one end, and a shoe or traveler constituting the sole and complete support of the other end, said traveler having extended contact with the rail, and acting in conjunction with said driving wheel to carry the entire weight of the frame and parts thereon over and resting upon a rail to be ground, a grinding wheel mounted on the frame near the traveler and relatively distant from the driving wheel, adapted to engage said rail as determined by its relation with said traveler, and means to drive said grinding wheel.
13. A self-contained automatic grinding machine comprising the following instrumentalities: a truck frame, a grinding wheel and propelling wheels thereon, a motor on the truck, a driving connection from said motor to the grinding wheel, a driving connection from the motor to the propelling wheels, reversing means for the latter, automatically acting means wholly for feeding the grinding wheel vertically up and down on the frame, and a timing device controlling both the reversing means for the propelling wheel drive and the grinding wheel feed.
14. A self-contained automatic grinding machine comprising the following instrumentalities: a truck frame supported in constant relation to a rail to be ground, supporting and propelling wheels for said frame, a source of power, a grinding wheel on the frame, means for communicating power from said source to said grinding wheel, means normally supporting said grinding wheel out of engagement with the rail, power operated means for forcing the same down by degrees to the deepest point of a cut, and for thereafter raising it gradually until again out of engagement with the rail, and a timing device controlling both the reversing means and the grinding wheel feed.

adapted to cut the feed on and off and operable from each of two points, one on each side of the body of the main truck.

25. In a machine of the character described, a main truck frame and wheels, a grinder mounted on said truck and supported thereby in position to engage a rail surface, a source of power, reversible transmission gearing between said source of power and the truck wheels, together with an automatic feed for said grinding element operable through said reversible transmission gearing.

26. A machine of the character described comprising a main truck frame and wheels, a grinding element mounted on each side of said main truck frame and adapted to operate upon the rail surface on that side, said main truck frame having a transverse shaft, means on each of its opposite ends for feeding the corresponding grinding element positively toward and from the rail surface independently of the action of gravity, a source of power on said main truck, a reversible transmission gearing between said source of power and said truck wheels, which gearing imparts forward and reverse motion to said wheels and also operates said transverse shaft aforesaid to feed the grinding elements vertically of the rail surface.

27. In a machine of the character described, a main truck frame and wheels, a source of power, reversible transmission gearing on one axle of said truck comprising oppositely rotating power driven gears and an intermediate double throw clutch member splined to said axle, a rotating grinding element supported from each side of the said main truck frame, and means for synchronously and automatically feeding said grinding elements vertically to the rail surface comprising a second axle on said truck parallel to the first, provided with feeding means on each end thereof, and operable through the forward and reverse motion of the first named axle.

28. In a machine of the character described comprising a main truck frame and wheels, a rotary grinding element carried by said main truck frame, a source of power, a feeding mechanism for said grinding element separate from the main truck axles, transmission gearing between the source of power on the one hand and said feeding mechanism and a truck axle on the other.

29. A rail grinding machine having a frame, track wheels thereon, a grinding element thereon, means for driving the grinding element, and means for laterally adjusting the grinding element.

30. A rail grinding machine having a frame, track wheels thereon, a grinding element thereon, means for driving the grinding element, means for laterally adjusting

the grinding element, and means for laterally adjusting the track wheels.

31. A rail grinding machine having a frame, track wheels thereon, a grinding element thereon, means for driving the grinding element, means for laterally adjusting the grinding element, means for laterally adjusting the track wheels, and means for adjusting the driving connection of the grinding wheel to correspond with the direct adjustments.

32. In a machine of the character described, a main truck frame and wheels, together with supporting members on opposite sides of the machine adapted to engage a trackway and independently adjustable to the gage, a grinding element, and means for driving the same also supported on said truck, auxiliary supporting wheels for said main truck frame, and means whereby said frame may be suspended therefrom.

33. A machine of the character described comprising a main truck frame and wheels, a grinding element on each side of said frame in the plane of the wheels, means for independently adjusting the grinding wheels to gage, and auxiliary wheels on which said main frame may be supported together with means connecting the auxiliary wheels and the main truck and adapted for suspension of the main truck on said auxiliary wheels.

34. A machine of the character described, comprising a main truck frame and wheels, a grinding element and a track engaging support in close proximity to each other in approximately the same plane, together with a common shifting device connected to said grinding element and said support whereby they may be shifted simultaneously to gage.

35. A machine of the character described comprising a main truck frame and wheels, a laterally adjustable grinding wheel cradle, and a grinding wheel and a track engaging support mounted on and movable with said cradle.

36. A rail grinding machine comprising a truck adapted to travel along a trackway, a rotary grinding wheel mounted on said truck adapted to engage and operate upon a rail, means for driving said grinding wheel, and a spark guard on one side of said grinding wheel adapted to catch the material thrown from the wheel and prevent the same from lodging on the surface being ground whereby inaccuracies due to the presence of said material on the rail surface are avoided.

37. In a grinding machine, a grinding wheel truck carrying a grinding wheel and adapted to be propelled along a trackway with the grinding wheel in operative relation thereto, and a derailing truck associated therewith, said grinding wheel truck adapted to be hoisted from the trackway and supported upon said derailing truck, and a
